STRINGED MUSICAL INSTRUMENT

Walter J. Pelensky, 19C Manheim Gardens,
Philadelphia, Pa. 19144

Continuation of design application Ser. No. 251,857, May 9, 1972. This application Nov. 25, 1974, Ser. No.
527,132

Term of patent 14 years

Int. Cl. D17—03

U.S. Cl. D56—1 A

Fig. 2

Fig. 1

FIG. 1 is a front elevational view of a stringed musical instrument, specifically a Ukrainian kobza, showing my new design;

FIG. 2 is a left side elevational view with the strings omitted for convenience of illustration; and

FIG. 3 is a right side elevational view thereof.

This application is a continuation of design application Ser. No. 251,857, May 9, 1972.

I claim:

The ornamental design for a stringed musical instrument, as shown and described.
